J. L. JOIRIS,
SHOTGUN AND THE LIKE GUN,
APPLICATION FILED MAY 20, 1920.

Patented Sept. 7, 1920.

Inventor:

Jean Louis Joiris
By Lawrence Langner
Attorney.

UNITED STATES PATENT OFFICE.

JEAN LOUIS JOIRIS, OF WANDRE, BELGIUM.

SHOTGUN AND THE LIKE GUN.

1,351,952.

Specification of Letters Patent.

Patented Sept. 7, 1920.

Application filed May 20, 1920. Serial No. 382,975.

To all whom it may concern:

Be it known that I, JEAN LOUIS JOIRIS, manufacturer, a subject of the King of Belgium, and resident of Wandre, in the Kingdom of Belgium, have invented certain new and useful Improvements in Shotguns and the like Guns; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

This invention relates to a double barreled shot gun having a single trigger.

This gun has two hammers each resting in the cocked position on a sear, each of these two hammers being adapted to be cocked and released separately.

When these two hammers are cocked simultaneously, the first action on the trigger releases one of the hammers and the second operation of the trigger releases the other.

One of the sears is firmly attached to the trigger and has a movable abutment adapted to bear against a catch carried by the sear and adapted according to its position to carry with it or release the second sear.

This movable abutment may be under the action of a spring tending to bring it into the position where it controls the displacement of the second sear, the action of this spring being overcome when the hammer bearing against the first sear is cocked by a nose carried by this hammer so that this abutment is in the position in which it does not involve the displacement of the second sear.

This mechanism may be completed by a safety piece locking the said second sear as soon as the first sear has commenced its displacement and liberating it as soon as the trigger has resumed its position of repose.

The invention will be more particularly described with reference to the accompanying drawings in which:

Figure 1 is a perspective view of the fire-arm with a part broken away showing the trigger, the sear which is connected with it and the first hammer bearing upon this sear.

Fig. 2 is a view in perspective of the gun with a part broken away showing the second sear and the second hammer.

Fig. 3 shows the trigger and the sear connected with it.

Fig. 4 shows the second tumbler.

Fig. 5 the safety piece.

Fig. 6 the same safety piece in its position relative to the barrels and the sears.

Fig. 7 shows the second sear illustrated in Fig. 4 on another face.

In Figs. 1 and 2 the hammers 1 and 2 are in the uncocked position, they are pivoted on the pin 3 and are each provided with two stop notches 4 and 5, those of the hammer 1 being adapted to bear against the sear 6 and those of the hammer 2 on the sear 7. These sears which are specially shown in Figs. 3 and 4 are pivoted on the pin 11. The hammer 1 has further a nose 8 which acts when the hammer is cocked, on the movable abutment 9 carried by the sear 6 in such a way as to displace it, as shown by the arrow X, against the action of a spring 10, and to bring it into such a position that it does not carry with it the abutment 12 attached to the sear 7. This abutment 12 has an escapement piece 13 pivoted at 14 upon it intended to give passage to the movable abutment 9 when this abutment is displaced as shown by the arrow X. The escapement piece 13 bears against the sear 7 by spring pressure.

The sear 7 has at its lower face a spring 25 acting constantly on the plate 26 of the trigger 27 and allowing this sear 7 a displacement relatively to the said plate 26 when during the cocking of the hammer 2 the catch notch 5 pushes it before taking support on it.

The working of the weapon is as follows:

When the hammer 2 is cocked its stop notch 5 bears on the projection 23 of the sear 7. During the cocking of the hammer 1 the nose 8 causes a displacement in the direction indicated by the arrow X, of the movable abutment 9.

The stop notch 5 of this hammer 1 before resting on the projection 21 of the sear 6 causes a slight displacement of this sear against the action of the spring 28 of the trigger 27, and during this displacement the escapement piece 13 allows of the passage of the movable abutment 9 without necessitating a displacement of the sear 7.

When the hammer 1 is cocked its stop notch 5 bears on the projection 21 of the sear 6 and the movable abutment 9 is re-

tained by the nose 8 of the hammer 1 in such a position that when the sear 6 is displaced it abuts neither against the catch 12 nor against the escapement piece 13, but on the contrary it slips on the edge 29 of this piece 13 as soon as in consequence of the firing of the hammer 1 the nose 8 has abandoned it.

When the trigger 27 is allowed to return to its position of repose, the removable abutment 9 is brought back in rear of the escapement piece 13 on which it takes support and obeying the action of its spring 10 assumes such a position that when the trigger 27 is afresh acted on, it will abut against the catch 12 and by this fact draw the tumbler 7, which will cause the firing of the hammer 2. This mechanism is completed by a safety piece 15 provided with a prolongation 16 entering the groove 17 of the action body (Figs. 1 and 2) and through which a pivot 18 passes. This piece 15 comprises a rib 19 adapted to engage between the projections 20 and 21 of the sear 6 and a finger 22 adapted to abut against the projection 23 of the sear 7 so as to cause the locking of this latter. This safety piece is constantly induced to cause this locking owing to a spring 24 acting on it.

As soon as, in consequence of the action on the trigger 27, the sear 6 commences to turn about its axis 11, the rib 19 of the part 15 penetrates between the projections 20 and 21 of the sear 6, and consequently the finger 22 abuts against the projection 23 of the sear 7 and locks this latter. When by releasing the trigger 27 it is allowed to resume its position of repose, the slope 30 of the sear 6 acting on the slope 31 of the safety piece 15 causes the displacement of this latter against the action of the spring 24 which liberates the sear 7.

It is easily evident from this that when one or other of the two hammers is cocked separately its firing is caused by the first action on the trigger.

It is evident that the principle of the trigger mechanism forming the object of the present invention may be applied to any kind of firearms such for example as pistols or revolvers.

What I claim is:

1. A double-barreled gun comprising two hammers, a single trigger pivotally mounted on a pin, a sear for one of the hammers attached firmly to the trigger, a second sear for the other hammer pivotally mounted on the aforesaid pin, and a movable abutment on the first sear adapted according to its position to operate and to release the second sear.

2. A double-barreled gun comprising two

hammers, a single trigger pivotally mounted on a pin, a sear for one of the hammers attached firmly to the trigger, a second sear for the second hammer pivotally mounted on the aforesaid pin, a movable abutment on the first sear adapted according to its position to operate and to release the second sear, a spring pressing said movable abutment toward the position in which it causes the displacement of the second sear, a nose on the first hammer acting on the movable abutment against the spring pressure when the hammer is cocked, for bringing said abutment into the position in which it does not operate the second sear.

3. A double-barreled gun comprising two hammers, a single trigger pivotally mounted on a pin, a sear for one of the hammers attached firmly to said trigger, a second sear for the second hammer pivotally mounted on the aforesaid pin, a movable abutment on the first sear adapted according to its position to operate and to release the second sear, a safety piece pivotally mounted in the action body, a rib on said safety piece adapted to penetrate between two projections of the first sear, in consequence of the displacement of the first sear, a slope on one of said projections acting on a slope of the aforesaid rib for moving the safety piece when the trigger has returned to its position of repose, and a finger on said safety piece, adapted to abut against a projection of the second sear when the rib of said piece is in engagement with the two projections of the first sear.

4. A double barreled gun comprising two hammers, a single trigger pivotally mounted on a pin, a sear for one of the hammers attached firmly to the trigger, a second sear for the second hammer pivotally mounted on the aforesaid pin, a movable abutment on the first sear adapted according to its position to operate and to release the second sear, a spring pressing said movable abutment toward the position in which it causes the displacement of the second sear, a nose on the first hammer acting on the movable abutment against the spring pressure when the hammer is cocked, for bringing said abutment into the position in which it does not operate the second sear, and an escapement piece arranged on the second sear for allowing of the displacement of the movable abutment.

In testimony whereof I affix my signature in presence of two witnesses.

JEAN LOUIS JOIRIS.
